UNITED STATES PATENT OFFICE.

JAMES F. DURBIN AND VOTAW S. DURBIN, OF FORT SCOTT, KANSAS.

RAILWAY-CAR COUPLING.

1,019,138.

Specification of Letters Patent.

Patented Mar. 5, 1912.

Application filed October 27, 1909. Serial No. 524,804.

To all whom it may concern:

Be it known that we, JAMES F. DURBIN and VOTAW S. DURBIN, citizens of the United States, residing at Fort Scott, in the county of Bourbon and State of Kansas, have invented certain new and useful Improvements in Railway-Car Couplings, of which the following is a specification.

This invention relates to railway car couplings, and pertains more particularly to the type of coupling embodied in the description set forth in our application #506,998, filed July 10th, 1909, in which, generally speaking, opposing heads are provided with eccentrically pivoted knuckles having offset projections which are adapted to be engaged and latched behind latch pins which are vertically slidable through the center of said heads.

20 The object of the invention is to provide a coupling, in which the self-opening knuckles are provided with improved means whereby they are locked in closed position.

It is also the object to provide said 25 knuckle locking or latching means of such structure that the self-opening knuckle will aid or complete the opening of the latch member.

In furtherance of the last mentioned object it is the purpose to provide a coupling in which the latch pin requires merely to be started, and the self-opening knuckle will then act on said latch pin to remove the latter a sufficient distance out of the way to 35 permit the complete opening of the knuckle.

With the above and other objects, which will hereinafter appear, in view our invention will now be fully set forth and described, reference being had to the accompanying drawings, in which—

Figure 1 is a longitudinal sectional elevation through the head of a coupling member, showing the knuckle in locked position, Fig. 2 is a cross sectional elevation through the 45 coupling head, Fig. 3 is a perspective view of the latch pin, and Figs. 4 and 5 are perspective views of the knuckle employed in our improved device.

Referring more particularly to said drawings, 1 indicates the coupling heads each of which is provided with a knuckle 2, pivoted at one side of the head as upon the pivot pin 3, and having a latch member or shank 4, which projects and operates within the cavity formed in each head.

More particularly each of the knuckles 2

consists of a locking head portion having the rearwardly projecting shank 4, which in cross section is substantially a continuation of the head portion projected rearwardly 60 from one side thereof, and terminates in a portion 5 having a face 6 which is adapted to project alongside of and beyond the locking or latching means, when the knuckle is in closed position. Said head portion of 65 the knuckle 2 is formed substantially of the same height or slightly longer than the height of the head 1, and tapers from top to bottom. Said head portion is also provided with curved inner and outer faces. The 70 knuckle 2 is thereby adapted to interlock with a similarly formed head carried by an opposing coupling head. The knuckle 2 is pivoted to the head 1 intermediate the 75 length of the shank portion 4, on the above 80 mentioned pivot pin 3, which latter is journaled centrally in projections formed at one side of the head 1. The lower face of the shank near its inner end, is beveled to conform to the beveled face of an incline 7 85 formed on the inside of the head 1 to oppose said beveled portion of the shank 4, whereby to cause the knuckle 2 to ride vertically up and down upon its pivot pin 3 as the shank 4 swings to and fro in the recesses formed in 90 said head 1 and is operated on by the bevel 7.

Located within the cavity of the coupling head 1, and in the rear central portion thereof is a latch pin 8. Said latch pin, 95 when in its lowered position hangs from a pin 9, and projects into an aperture 10 formed through the bottom of the head 1, said pin 9 being adapted to operate in a slot formed in said latch pin 8. The upper end of said latch pin 8 projects into a dome 11 formed on the top, and preferably integral therewith, of the head 1 and being formed with a cavity 12 which communicates with the interior of the head 1 through an opening 13 in which the latch pin works. As before stated, said latch pin 8 is provided with a slot, 100 through which the pin 9 projects to support said latch pin, and the lower portion of said latch pin is provided at one side with a recess in which is pivotally mounted a ring 14 to which a chain 15 is secured, said chain being then passed through an aperture 16, formed in the upper portion of the head 1 at one side thereof. Formed preferably integral with the inner portion of the head 1, 105 and inclined oppositely to the said incline 7 is a track-way 17, said track-way lying in 110

the same vertical transverse plane in which the latch pin 8 lies, and as the latch pin is raised from its normal position by lifting on chain 15 the lower end 18 of said latch 5 pin will be carried out of the aperture 10 and swung over upon the surface of the track-way 17, after which the lower end of said latch pin is in position to ride freely upon said track-way. The lower portion of 10 the latch pin 8 is provided with an offset 20, affording on its upper side an inclined surface 21. This inclined surface 21 acts as an abutment or stop which strikes against the upper portion of the coupling head to limit 15 the upward movement of the latch pin 8.

Now, from our former application, the action of the knuckle 2, after the latter has been unlatched will be readily understood, in that it is actuated by gravity to swing 20 outwardly and to one side away from the front of the head 1 to its unlocked position. Also, the operation of our improved latch 25 pin will be evident from the above description. If the knuckle 2 is in the locked position shown in Fig. 1, it will be only necessary to lift upwardly upon the chain 15 until the lower end 18 of the latch pin 8 is lifted upon the track-way 17. The pin being 30 so mounted that its movement upon the track-way is practically unrestricted, the force of gravity which actuates the knuckle 2 to open the latter will also cause the shank 4 of said knuckle 2 to push against the pin 8 and cause the latter to continue its course 35 upwardly on the track-way 17, thereby gradually pushing it out of the path of said shank 4 and permitting the latter to ride partly by and in front of the same until the knuckle 2 has reached its open position. 40 When in this position, the outer end of the shank 4 will still engage the latch-pin and prevent it from swinging back and dropping into locking position. When it is desired to lock the knuckle 2 in its closed position, 45 the latch pin 8 is raised to the limit of its upward movement by means of the chain 15, until the knuckle has been swung to closed position, thereby carrying the shank 4 to its innermost position where it rests upon the incline 7, and the latch pin 8 is then released, and rides of its own weight down the track-way 17, and drops into the aperture 10, thereby locking the knuckle in closed position. 50

55 From the above description, and the exposition of its operation, it will be evident that our improved coupling head latching device is an efficient and practicable structure. Except for the slight pull required to 60 lift the pin initially out of the aperture 10,

the knuckle is practically self-unlocking and opening, and also, when the knuckle is swung into its closed position the mere action of dropping the latch pin is sufficient to permit it to fall by gravity into position 65 to lock the shank of the knuckle.

Having thus fully described our invention, what we desire to claim and secure by Letters Patent of the United States is:—

1. A car coupling, comprising, in combination, a head, a self-opening knuckle pivoted to said head and having an extended shank, a pivoted, vertically-movable latch-pin located in the path of movement of said shank and adapted to engage a fixed part 70 of the head to lock the knuckle, said latch-pin being adapted, when released from such engagement, to be moved to one side by the shank when the knuckle swings to open position.

2. A car coupling, comprising, in combination, a head, a knuckle, a shank carried by said knuckle, a slotted latch-pin pivotally suspended in front of said shank and having locking engagement with the head, 80 a track-way formed in said head, and means for releasing said latch-pin, the latter being adapted to be moved over said track-way by the shank in the opening movement of the knuckle.

3. A car coupling, comprising, in combination, a head having a track-way formed therein, a knuckle, a shank carried by said knuckle, and a vertically movable latch-pin suspended in front of said shank and engaging at its lower end a fixed part of the head, said latch-pin, when released from such engagement, being adapted to have its lower end moved over said track-way by the shank in the opening movement of the 90 knuckle.

4. A car coupling, comprising, in combination, a head having a track-way formed therein, a self-opening knuckle, a shank carried by said knuckle, a vertically movable latch-pin pivotally suspended in front of said shank and adapted to have its lower end engage a fixed part of the head, and means for raising said latch-pin and thereby releasing said knuckle, said latch-pin being adapted to be carried up said track-way automatically by the movement of the shank 100 as the knuckle opens.

In testimony whereof we affix our signatures in presence of two witnesses.
